WINDING UP MECHANISM FOR TIME
CLOCKS OF VEHICLES

Friedrich K. H. Nallinger, Stuttgart, Germany

Application August 14, 1950, Serial No. 179,265

1 Claim. (Cl. 58-46)

1

My invention relates to a fluid-operated device for winding a spring-driven clock, more particularly a vehicle clock of the type having an arbor capable of rotating in one direction only for winding up the spring of the clock.

This application is a continuation-in-part of application Ser. No. 176,345, filed July 28, 1950, now Patent 2,574,583, issued November 13, 1951.

It is the object of the present invention to provide means whereby the transfer of an excessive winding force from the fluid-operated member to said arbor will be prevented. It is a further object of my invention to provide a fluid-operated device of the character indicated which is extremely simple, lends itself to manufacture at a low cost, and is reliable in operation and free from any substantial wear.

Further objects of my invention will appear from a preferred embodiment thereof described hereinafter with reference to the accompanying drawing in which

Fig. 1 is a side view of a preferred embodiment showing the time clock and the fluid-operated winding device combined therewith, the latter being partly shown in section,

Fig. 2 is an elevation viewed from the left with reference to Fig. 1, and

Fig. 3 is a section taken along the line 3-3 of Fig. 2.

In the instrument panel of the vehicle, a clock 10 is installed having an arbor 11 which is capable of rotating in one direction only for winding up the spring of the clock and of axial displacement for setting the clock. The arbor 11 has the usual knurled knob 12 at its lower end for manipulation. If the driver of the vehicle wishes to set the clock he will grasp the knob to shift the arbor 11 in axial direction whereby it will be coupled to the hands of the clock in a known manner.

For the purpose of winding up the clock automatically, I have provided the following means: On the rear wall of the clock 10 located at the left with reference to Fig. 1 there is mounted a substantially cylindrical sheet metal housing 13 which as a whole is composed of two flanged cup-shaped sheet metal shells 14 and 15. Between the adjacent flanges of the shells 14 and 15 a corrugated diaphragm 16 is interposed which forms a partition subdividing the interior of the housing 13 into chambers. The chamber within the shell 14 is connected with a pipe 17 which establishes a communication with the intake manifold of the engine of the vehicle. The shell 15 is provided with an axially disposed boss 18 having an axial

2

bore in which a stem 19 is slidably guided. The inner end of the stem is firmly connected to the center of the diaphragm 16, whereas the outer end carries a cross head 20. A similar cross head 21 is mounted on housing 13 near the periphery thereof by a stud 22. A leaf spring 23 extends across the cross heads 20 and 21 and is firmly held in contact therewith by clamping members 24 and 25 which are suitably fixed to the cross heads 20 and 21, for instance by means of rivets 26 shown in Fig. 2.

The lower end of the leaf spring 23 projects downwardly beyond the cross head 21 and is connected by a link 27 to an arm 28 which is mounted 15 for rotation about the axis of the arbor 11 and is connected therewith by a one-way clutch. In the embodiment shown, the one-way clutch comprises an inner element 29 keyed to the arbor 11 and an outer surrounding annular element 30 fixed to 20 arm 28. The two elements confine tapered pockets in which one-way clutching means in the form of rollers 31 are inserted. The link 27 is attached to the leaf spring 23 by a cross head 32 fixed to link 27 and by means of a clamping member 33 25 riveted to the cross head 32, the spring being inserted therebetween. The opposed faces of the cross heads 20, 21 and 32 and of the clamping members 24, 25 and 33 are preferably convex as shown in Fig. 1, and the leaf spring is so loosely 30 held between the cross head 21 and the clamping member 25 as to be capable of a rocking motion on cross head 21. Thus, it will appear that means are provided to connect spaced points of the leaf spring 23 to the diaphragm 16, the housing 13 and 35 the link 27.

The operation is as follows: Whenever the operator by starting the engine and depressing the accelerator causes vacuum to be built up in the intake manifold of the engine, air will be sucked 40 through pipe 17 from the shell 14 causing the diaphragm 16 to pull stem 19 into casing 13. As a result, the leaf spring 23 will tend to oscillate about its central supporting point on cross head 21 and to pull link 27 to the left with reference 45 to Fig. 3 whereby the annular element 30 will be rotated in clockwise direction with reference to Fig. 3. The one-way clutch will transfer such rotary motion to the arbor 11. Whenever the intake manifold of the engine is relieved from 50 vacuum, the parts 16, 19, 23, 27 and 30 will move in the opposite direction and this movement will not be transferred to the arbor, since the arm 28 is mounted for a free and unobstructed rocking motion opposite to the winding direction. When 55 the clock has been fully wound up, the arbor 11

is unable to further rotate in clockwise direction with reference to Fig. 3. Therefore, the lower end of leaf spring 23 cannot move to the left when stem 19 is pulled inwardly into housing 13. In that event, the leaf spring 23 will be flexed so that any damage to the clock by overwinding will be effectively prevented.

Thus, the leaf spring 23 serves the dual purpose of transferring the winding motion to the one-way clutch and of limiting the winding couple so transferred.

What I claim is:

In a device of the character described, a spring-driven clock having a casing and a spring arbor projecting therefrom, a diaphragm housing 15 mounted on the casing of said clock, a diaphragm in said housing, a swingable member rotatably mounted on the arbor of said clock, means co-operatively co-ordinated to said swingable member and said arbor and constituting a one-way 20

clutch therebetween, a linkage attached to said swingable member, a leaf spring, and means connecting spaced points of said leaf spring to said diaphragm, to said housing and to said link.
